UNITED STATES PATENT OFFICE.

WALTER P. HOPWOOD AND PHILIP H. KROH, OF BALTIMORE, MARYLAND.

WHEEL-HUB.

1,139,867.

Specification of Letters Patent. Patented May 18, 1915.

Application filed August 26, 1911. Serial No. 646,227.

To all whom it may concern:

Be it known that we, WALTER P. HOPWOOD and PHILIP H. KROH, citizens of the United States, residing at Baltimore, in the State of Maryland, have invented a new and useful Wheel-Hub; and we do hereby declare the following to be a full, clear, and exact description of the invention, such as will enable others skilled in the art to which it appertains to make and use the same.

This invention relates to a new and useful hub construction for wagon wheels.

The main object of the invention is to improve and simplify the general construction of wheel hubs.

A further object of the invention is to provide a hub including several sections, and provided with means for locking the sections together about a body of the hub.

The invention comprises further features and combination of parts as hereinafter set forth, shown in the drawings and claimed.

In the drawings:—Figure 1 is a view in the elevation of the hub, showing the back section thereof removed, and disposed in a position ready to be fitted on the hub, showing the locking means between it and the hub. Fig. 2 is a longitudinal sectional view through the hub. Fig. 3 is a view on line 3—3 of Fig. 2.

Referring more particularly to the drawings 1 designates the central body member having the usual inner metal bearing sleeve. The body member may be made of any suitable material but in the present instance, the same is constructed of wood or similar fiber. Adjacent the inner end of the body member, an annular shoulder is provided, designated by the character 2. Fitting telescopically over the body member, and in contact with the shoulder 2 is the central sleeve section 3, in which the spokes 4 of the hub are secured, as shown at 4^a. The central sleeve section, at each peripheral edge thereof, is provided with annular grooves 5 and 6. The central sleeve section is spaced apart from the hub member. The outer end of the body member is constructed with an annular bevel, which terminates into an annular shoulder 8. Fitting telescopically over the outer end of the body member is a metallic sleeve 9. This metallic sleeve 9 upon its inner circumference is provided with shoulders 10 and 11. The shoulder 11, contacts with the shoulder 8, while the shoulder 10 contacts with the peripheral edge of the

central section of the hub, as shown at 12. Between the shoulders 10 and 11 annular bulges 13 are formed, which contact with the bevel 7. By these shoulders a wedge 60 connection is maintained between the sleeve 9 and the body of the hub, there being an enlargement of white lead or other cement between the bulges 13, to assist in holding the sleeve 9 in place. The portion 14 of the 65 metallic sleeve 9 beyond the shoulder 10 fits into the annular groove 6, there being a deposit of white lead, or other cement or plastic material arranged in the groove, for holding the sleeve 9 to the central section. 70 By the provision of the annular bulges of the sleeve 9, and the enlargement of white lead or other cement, the sleeve 9 is held in place. The sleeve 15 fits telescopically over the inner end of the body member, with the 75 portion 16 thereof fitted and cemented by white lead or other plastic material into the groove 5, as shown in the drawings. The sleeve 15 approximately fits the bevel 18 of the hub, there being a deposit of white lead 80 or other plastic material 17 arranged between the sleeve 15, and the bevel 18, so as to assist in holding the sleeve 15 in position. The inner end of the body or hub is provided with short longitudinal grooves 19, which 85 are adjoined by the lateral portions 20. The sleeve 15 is forced on the body or hub, by ten to forty ton pressure. When the sleeve 15 is forced on the body, the lugs 21 cut the grooves 19 to hold the sleeve 15 on the hub 90 member. By this arrangement, in combination with the deposit of plastic material 17, the sleeve 15 is held securely in place. The spokes which are arranged in the central 95 section extend partially into the body member of the hub, as shown at 22.

From the foregoing it will be noted that there has been produced a simple, novel, and efficient hub construction, and one which has been found to be practical.

The invention having been set forth, what is claimed as new and useful is:—

1. In combination, a hub member, a central hub sleeve section on the hub member and spaced apart therefrom including a deposit of white lead therebetween, said central hub sleeve section having an annular groove at each end, a sleeve fitting the outer end of the hub member and seated in one of the grooves of the central hub section, an enlargement of white lead between the hub member and the outer sleeve, an inner sleeve

fitting the inner end of the hub member and seated in the other groove of the central hub section, deposits of white lead in said grooves to seal the inner and outer sleeves to the central hub section, the central hub section having radial tapering openings, the hub member having recesses registering with said openings, and spokes corresponding in shape to fit said openings and said recesses, thereby constituting means to hold the central hub section spaced apart equally from the hub member, so that the deposit of white lead may be arranged in the hub section and hub member when assembling such parts.

2. In combination, a hub member, a central hub sleeve section on the hub member and spaced apart therefrom including a deposit of white lead therebetween, said central hub sleeve section having radial tapering openings, the hub member having re-

cesses registering with said opening, spokes having their inner ends shaped to fit the openings and said recesses, thereby constituting means to hold the central hub sleeve section spaced apart equally from the hub member, so that the deposit of white lead may be arranged between the hub sleeve section and the hub member when assembling such parts, and sleeves, one secured to each end of the hub member and being secured to the central hub sleeve section to hold the central section in place.

In testimony whereof we have signed our names to this specification in the presence of two subscribing witnesses.

WALTER P. HOPWOOD.
PHILIP H. KROH.
